UNITED STATES PATENT OFFICE

MAX L. WATERMAN, OF FAIRFIELD, CONNECTICUT, ASSIGNOR TO THE SINGER MANUFACTURING COMPANY, OF ELIZABETH, NEW JERSEY, A CORPORATION OF NEW JERSEY

SEWING MACHINE LOOP-TAKER

Application filed December 24, 1930. Serial No. 504,613.

This invention relates to improvements in sewing machine loop-takers and aims to provide a loop-taker having separable and mutually embracing cylindrical body-sections 5 with a loop-seizing beak bent outwardly away from the loop-taker axis beyond the peripheral surface of the outer body-section. A further object of the invention is to provide for ready removal of the bobbin of a vertical-axis loop-taker, partially underlying the sewing machine throat-plate and having separable and mutually embracing cylindrical body-sections together defining a raceway for the bobbin-carrier. 10 The foregoing and other objects and advantages in view, together with means whereby the same may be carried into effect, will best be understood from the following description of a preferred embodiment of the 15 invention illustrated in the accompanying drawing, in which:

Fig. 1 is a top plan view of the improved loop-taker, including the bobbin-carrier and bobbin. Fig. 2 is a side elevation of the loop-taker. Fig. 3 is a sectional view substantially on the line 3—3 of Fig. 1. Figs. 4 and 5 are perspective views of respectively the outer and inner body-sections of the loop-taker. Fig. 6 is a sectional view of the loop-taker body-sections substantially on the line 6—6 of Fig. 2.

The present loop-taker was designed more particularly as an improvement on the rotary hook forming the subject of the U. S. patent 35 to W. N. Parkes, issued Feb. 19, 1924, under No. 1,484,151.

The loop-taker comprises an outer cylindrical body-section 1 closely embracing an inner cylindrical body-section 2 having a base 3 provided on its outer side with an annular rib 4 serving to locate the outer body-section. Depending centrally from the base 3 is a hollow stub-shaft 5 adapted to be connected with suitable actuating mechanism (not shown) for rotating the loop-taker. The

outer body-section 1 of the loop-taker is fixedly but detachably secured upon the inner body-section 2 by screws 6 passing through countersunk apertures 7 in the outer body-section 1 and threaded into apertures 8 provided in the thickened portion 9 of the inner body-section 2 adjacent to its base 3. 50

At its free end, the inner body-section 2 has an inwardly directed flange 10 and the outer body-section 1 similarly has an inwardly directed flange 11 overhanging the flange 10 and suitably spaced therefrom to provide a raceway 12 for a peripheral bearing rib 13 upon a bobbin-carrier 14 which is thereby journaled in the loop-taker body. A bobbin 15 is disposed within the usual thread-cavity in the bobbin-carrier 14, which latter is restrained against rotation with the loop-taker by any suitable means, in the present instance comprising a lug 16 depending from a throat-plate 17 to engage the walls of a notch 18 in a portion of the bobbin-carrier wall projecting beyond the loop-taker body. The throat-plate partly overlies the loop-taker and has feed-dog slots 19 and also an aperture 20 for a needle 21 which is endwise reciprocatory in a path substantially parallel with the axis of rotation of the loop-taker, it being understood from Fig. 3 of the accompanying drawing that the loop-taker illustrated is of the vertical-axis type. 70

The outer body-section 1 of the loop-taker is suitably cut away to provide thereupon a loop-seizing beak 22 and a loop-discharging spur 23, which latter is disposed in the cylindrical portion of the body-section 1. The loop-seizing beak 22 is, however, bent outwardly away from the axis of the loop-taker beyond said peripheral surface, as clearly illustrated in Figs. 1 and 6 of the drawing. By bending out the loop-taker beak in this manner, the axis of rotation of the loop-taker may be spaced sufficiently from the needle-path to provide for ready removal of the bobbin without interference 90

by the overlying throat-plate and consequently the regular principle of throat-plate construction may be followed, i. e., the edge of the throat-plate overlying the looper need not be cut away and unduly weakened adjacent the feed slots to provide the necessary bobbin-clearance.

The inner body-section 2 of the loop-taker is likewise cut away to provide a thread-loop 10 engaging nose 24 which engages the inner face of the loop-seizing beak 22 directly adjacent the point of said beak, whereby to insure that the needle-thread loop directly after seizure by said beak is deflected inwardly to 15 ward the side wall of the bobbin-carrier preparatory to being spread in the usual manner to be passed about said bobbin-carrier. To provide for the described contacting relationship between the beak 22 and the nose 24, 20 the latter is also bent outwardly away from the loop-taker axis beyond the cylindrical surface of the inner body-section 2, as illustrated more particularly in Fig. 6 of the drawing.

25 Because of the inwardly projecting raceway flange 11 of the body-section 1, it is obviously necessary to initially pass the cylindrical opposite end of said outer body-section 1 over the raceway-flange end of the inner body-section, when assembling said body-sections. To provide the necessary clearance for effecting the assembling of these parts, the outer body-section 1 is cut away below the beak 22 clear to the bottom of said 30 section, thereby in effect providing a split ring having a channel or gap 25 to admit the outwardly bent nose 24 of the inner body member. This construction therefore provides for readily assembling the body-sections of a loop-taker having the advantage of a bent out beak in addition to the advantages inherent in a loop-taker of the type described. The effect of the clearance-channel referred to might also be obtained by thinning the wall of the outer body-section at the required point or by bending or slightly crimping the wall of the outer body-section at, for instance, the location of the gap 25, instead of by entirely cutting away said wall. 40 45 50

Having thus set forth the nature of the invention, what I claim herein is:—

1. A rotary loop-taker for sewing machines having separable and mutually embracing inner and outer cylindrical body-sections, the inner body-section having a thread-loop engaging nose disposed within the outer body-section and extending outwardly away from the loop-taker axis beyond the cylindrical surface of said inner body-section, said outer section having an inner body-section-nose clearance channel extending to the base of the outer body-section and providing for separably uniting said body-sections in mutually embracing relationship.

65 2. A rotary loop-taker for sewing machines

having separable and mutually embracing inner and outer cylindrical body-sections, the outer body-section having a loop-seizing beak extending outwardly away from the loop-taker axis beyond the cylindrical surface of said outer body-section, the inner body-section having a thread-loop engaging nose disposed within the outer body-section adjacent to said loop-seizing beak and extending outwardly away from the loop-taker axis beyond the cylindrical surface of said inner body-section, and said outer body-section having an inner body-section-nose clearance channel extending to the base of the outer body-section and providing for separably uniting said body-sections in mutually embracing relationship. 70 75 80

3. A rotary loop-taker for sewing machines having separable and mutually embracing inner and outer cylindrical body-sections together defining a raceway, a bobbin-carrier journaled in said raceway, the inner body-section of the loop-taker having a thread-loop engaging nose extending outwardly away from the loop-taker axis beyond the cylindrical surface of said inner body-section, and the outer body-section having a loop-seizing beak extending outwardly away from the loop-taker axis beyond the cylindrical surface of the outer body-section, said outer body-section having a clearance-channel extending from its beak to the base of the outer body-section and providing for separably uniting said body-sections in mutually embracing relationship. 90 95 100

4. A rotary loop-taker for sewing machines having separable and mutually embracing inner and outer cylindrical body-sections together defining a raceway, a bobbin-carrier journaled in said raceway, the inner body-section of the loop-taker having a thread-loop engaging nose extending outwardly away from the loop-taker axis beyond the cylindrical surface of said inner body-section, the outer body-section having a loop-seizing beak in contact with said inner body-section nose extending outwardly away from the loop-taker axis beyond the cylindrical surface of the outer body-section, said outer body-section having a channel widthwise thereof in alignment with said inner body-section nose in a direction substantially parallel with the axis of rotation of the loop-taker, and said channel extending to the base of the outer body-section to thereby provide for separably uniting said body-sections in mutually embracing relationship. 105 110 115 120

5. In a sewing machine, a vertically reciprocating needle, a throat-plate having a needle aperture, a vertical axis rotary loop-taker partially underlying said throat-plate having separable and mutually embracing inner and outer cylindrical body-sections together defining a raceway, a bobbin-carrier journaled in said raceway, the outer body-section of said loop-taker being cut away to constitute 125 130

a split ring having a loop-seizing beak and a clearance gap adjacent the beak, said loop-seizing beak being bent outwardly from the cylindrical surface of said ring away from the loop-taker axis, and the inner body-section having an outwardly bent thread-loop engaging nose disposed in contact with the inner face of said outwardly bent loop-taker beak and in alignment with said clearance gap in a direction substantially parallel with the axis of rotation of the loop-taker.

In testimony whereof I have signed my name to this specification.

MAX L. WATERMAN.
